By

UNITED STATES PATENT OFFICE.

HENRY E. GRIZZARD, OF FRANKLIN, VIRGINIA.

DESIGN FOR A PAPER-CLIP.

44,957.

Specification for Design.

Patented Dec. 2, 1913.

Application filed June 21, 1913. Serial No. 775,145. Term of patent 7 years.

To all whom it may concern:

Be it known that I, HENRY E. GRIZZARD, a citizen of the United States, residing at Franklin, in the county of Southampton and State of Virginia, have invented a new, original, and ornamental Design for Paper-Clips, of which the following is a specification, reference being had to the accompanying drawing, forming a part thereof.

The figure is an elevation of a paper clip, showing my new design.

I claim:

The ornamental design for a paper clip, as shown.

HENRY E. GRIZZARD.

Witnesses:

A. G. BEAMAN,
THOS. D. BOONE.
